UNITED STATES PATENT OFFICE.

ALEXANDER J. LOGUIN, OF WEST ALLIS, WISCONSIN, ASSIGNEE, BY MESNE ASSIGNMENTS, TO ALLIS-CHALMERS MANUFACTURING COMPANY, A CORPORATION OF DELAWARE.

SWITCH.

1,175,279.

Specification of Letters Patent. Patented Mar. 11, 1916.

Application filed January 16, 1911. Serial No. 602,759.

To all whom it may concern:

Be it known that I, ALEXANDER J. LOGUIN, a subject of the Czar of Russia, residing at West Allis, in the county of Milwaukee and State of Wisconsin, have invented certain new and useful Improvements in Switches, of which the following is a full, clear, and exact specification.

This invention relates to electric switches or circuit-breakers.

Among the objects of this invention are to improve and simplify the construction of switches or circuit-breakers so that great pressure, to secure good electrical connection between the contacts, can be created upon the application of comparatively little power, and also to cheapen the cost of manufacturing switches.

The various novel features of my invention will be described in the specification and particularly set forth in the appended claims.

The invention is illustrated in the accompanying sheets of drawings, in which—

Figure 1 is a side elevation of my improved switch or circuit-breaker in a closed position; Fig. 2 is a side elevation of the same in an open position; Fig. 3 is a partial plan elevation of the same switch; and, Fig. 4 is a side elevation of a switch which is a modification of that shown in Figs. 1 and 2.

On the base 10, of suitable insulating material, are mounted two stationary contacts 11 and 12. Electrically connected to these contacts and extending through the base 10 are bolts 13 and 14 respectively. The lower ends of these stationary contacts 11 and 12 are provided with stops 15 which will be considered hereinafter. On the base 10 is also a support 16 for the movable parts of the switch. An actuating member or handle 17 is pivotally connected to the support 16 at the point 17^a. This actuating member is also pivoted at the point 18 to a member or arm 19 which carries at one end thereof a movable contact 20. This movable contact 20 is preferably laminated and bow-shaped, being adapted to engage and bridge the stationary contacts 11 and 12. The movable contact is supported in the holder 21 which is connected to the arm 19 by a link 22. This link, which forms a flexible connection between the movable contact 20 and arm 19, is so biased by a spring 23 that the holder 21 is held against the arm 19

when the switch is in an open position and has the same tendency when the switch is in a closed position. Another link 24 flexibly connects the contact-carrying arm 19 with the support 16 in which said link is pivoted at the point 25. By means of this simple arrangement an effective mechanical system is provided for clamping the movable contact 20 into firm engagement with the stationary contacts 11 and 12. With this construction, upon the application of comparatively little power an immense pressure between the contacts is obtained.

The switch is shown in open position in Fig. 2.

By depressing the handle or actuating member 17, said member will swing about its pivotal point 17^a as a center, drawing down the contact carrying arm 19. In addition to the movement of this arm 19 being controlled by the actuating member 17, it is directed by the link 24 which is pivoted to the support 16 at 25. This pivotal point is a center about which the arm 19 moves. Upon the continued downward movement of the actuating member the movable contact 20 is brought into engagement with the stationary contacts, whereupon the movable contact slides over the stationary contacts with increasing pressure until the friction between the stationary and movable contacts overcomes the strength of the spring 23. At this point the movable contact ceases to slide over the stationary contacts and the contact-carrying arm 19 is given a further downward or gliding movement, cramping with great pressure the movable contact into a more firm and secure connection with the stationary contact. Upon this last gliding movement of the arm 19 the link 24 is brought more nearly to a horizontal position and naturally forces the contact-carrying arm 19 closer to the base 10. It is to be observed, however, that with the switch in a closed position the links 22 and 24 are not in exact horizontal positions. Although a still greater pressure would be obtained if said links were forced into a horizontal position they are retained in the position indicated in Fig. 1 so that the movable parts of the switch preferably will not be on a dead center. If for any reason the movable contact should slide over the stationary contacts beyond a predetermined desirable amount it will come into engagement with

the stops 15, whereupon the contact carrying arm 19 will be moved into its final cramping position.

As soon as the parts have been brought 5 fully into closed position, as shown in Fig. 1, a latch 27 on the actuating member 17 engages a latch 28 which is pivotally mounted in the support 16. Formed integrally with the latch 28 is an armature 29 10 of an overload magnet 30. The latch 28 is biased to a locking position and the armature 29 held away from the core 31 of the magnet 30 by a spring 32. The latch 27 of the handle is also biased to a locking position by a spring 33. The switch being closed, current can pass from the bolt 14, through one stationary contact 12, movable contact 20, the other stationary contact 11, and bolt 13. From bolt 13 the circuit may extend, by suitable connections, through the coil of the overload magnet 30 to a switch terminal 34. In case of an overload, the armature 29 will be attracted to the core of the overload magnet and the latches 27 and 28 will 15 be drawn out of engagement with each other, permitting the switch to open. The parts 27 and 28 may also be disengaged manually by a thumb button 35 on the latch 27. Upon such disengagement, the coöperating relatively movable contacts will be forced apart 20 quickly by the action of a spring 36, the ends of which engage the contact carrying arm 19 and actuating member 17.

By means of the arrangement of the actuating member 17 and contact carrying member 19 with its linkage connections with the support 16 and movable contact member 21 respectively, the switch contacts can be brought into effective engagement with a 25 maximum pressure upon the application of comparatively little power, and the contacts disengaged with great rapidity when the latches 27 and 28 are caused to unlock. The movement of the movable contact upon the 30 opening of the switch being a rapid one, any arc which may be formed is almost immediately broken.

In Fig. 4 a modification of the invention shown in Figs. 1 and 2 is illustrated. Instead of using the link 24 as shown in Fig. 1 a bearing member or roller 37 is secured in the support 16, and is adapted to be engaged by the contact-carrying arm 19. Assuming that the switch in Fig. 4 is in an 35 open position and is being closed the contact-carrying arm 19 will slide over the bearing member 37 with the movable contact 20 gradually nearing the stationary contacts. When the movable contact comes into 40 engagement with the stationary contacts and the friction therebetween has overcome the strength of the spring 23, the contact-carrying arm 19 will be given its final gliding movement and due to its coöperation with 45 the link 22 and bearing member 37, the

pressure between the stationary and movable contacts will be increased to a maximum.

There may be many modifications in the precise form and arrangement herein shown 5 and described and I aim to cover all such modifications which do not involve a departure from the spirit and scope of my invention as set forth in the appended claims. 75

What I claim as new is:

1. In a switch, the combination of a fixed contact, a movable contact, a member on which said movable contact is movably mounted, and actuating means for said member comprising means for causing the final closing movement of said movable contact to be approximately parallel to the engaging surface of said fixed contact, and said actuating means coöperating with said movable mounting to increase the pressure with which said movable contact bears on 80 said fixed contact.

2. In a switch, the combination of relatively movable contacts, a member carrying 90 one of said contacts, a link connecting said one contact and said member and biased to draw said contact toward said member, a support, and means associated with said support and said member for actuating said member to move said contacts into closed position and to produce relative separation between said one contact and said member. 95

3. In a switch, the combination of a support, relatively movable contacts, a supporting arm carrying one of said contacts, a connection between said arm and the contact carried thereby permitting relative separation and approach of said arm and its contact, said latter contact being normally 105 biased toward said arm, and actuating means comprising a plurality of elements connected to said support and said arm at different points for causing the desired switch closing operation of said contact carrying arm. 110

4. In a switch, the combination of a support, relatively movable contacts, a member carrying one of said contacts and connected thereto by means permitting relative separation and approach of said member and the contact carried thereby, and means operative during the closing movement of said switch 115 to cause movement of said member and its contact together and subsequently to act in 120 coöperation with said member and said contacts to cause relative movement between said member and the contact carried thereby.

5. In a switch, the combination of a stationary contact having a stop, a movable contact adapted to engage said stop to be limited in movement in the plane of the engaging surface of said fixed contact, a member 125 flexibly connected to said movable con- 130

tact, a support, a link connecting said member and said support, and means for actuating said member, said link coöperating with said actuating means to force said movable contact to move in a plane parallel to the engaging surface of said fixed contact during a part of its movement.

6. In a switch, the combination of a stationary contact, a movable contact, a member on which said movable contact is movably mounted, a support, said member being movably mounted on said support, and an actuator for pressing said movable contact into engagement with the stationary contact, the movable mounting of said movable contact and said member coöperating with said actuator to cause said movable contact to first move over said stationary contact with a wiping action and then causing relative movement between said movable contact and said member.

7. In a switch, the combination of a stationary contact, a movable contact, a member on which said movable contact is movably mounted, and means for actuating said member to press said movable contact into engagement with the stationary contact, said movable contact first moving over said stationary contact with a wiping action and then said actuating means coöperating with said movable mounting to cause a relative movement between said movable contact and said member.

8. In a switch, the combination of a stationary contact, a movable contact, a member associated with said movable contact, a link connecting said movable contact and said member to permit said member to move to and from said movable contact, and means for actuating said member to press said movable contact into engagement with said stationary contact, said movable contact first moving over said stationary contact with a wiping action and then said actuating means coöperating with said link to produce relative separation between said movable contact and said member.

9. In a switch, the combination of a fixed

contact, a coöperative movable contact, and actuating means for said movable contact effective during the switch-closing operation to cause movement of said movable contact in a direction approximately parallel to the engaging surface of said fixed contact when said contacts are first brought into engagement and to subsequently increase the pressure with which said movable contact bears on said fixed contact.

10. In a switch, a support, a fixed contact, a member having a contact portion adapted to engage said fixed contact, links connected at one end to said member and at the other end to said support, said links being connected to said member and said support at different points thereon, and means for imparting motion to one of said links to actuate said member, a portion of the latter part of the closing movement of the points of said links connected to said member being approximately parallel to the engaging surface of said fixed contact, whereby a wiping action between said fixed and movable contacts is secured.

11. In a switch, the combination of a fixed contact, a coöperative movable contact, a member on which said movable contact is movably mounted, and actuating means for said member operative during switch-closing movement to cause movement of said contact in a direction approximately parallel to the engaging surface of said fixed contact after said contacts are first brought into engagement, said actuating means coöperating with the movable mounting of said movable contact during the latter part of the switch-closing operation to increase the pressure with which said movable contact bears on said fixed contact.

Milwaukee, Wis., Jan. 9, 1911.

In testimony whereof I affix my signature, in the presence of two witnesses.

ALEXANDER J. LOGUIN.
